UNITED STATES PATENT OFFICE.

WALTER L. WILKS, OF WALLINGFORD, CONNECTICUT, ASSIGNOR TO THE
SIMEON L. AND GEORGE H. ROGERS CO., OF SAME PLACE.

DESIGN FOR A HANDLE FOR SPOONS, FORKS, OR SIMILAR ARTICLES.

SPECIFICATION forming part of Design No. 34,525, dated May 21, 1901.

Application filed April 22, 1901. Serial No. 57,021. Term of patent 7 years.

To all whom it may concern:

Be it known that I, WALTER L. WILKS, of Wallingford, in the county of New Haven and State of Connecticut, have invented and produced a new Design for a Handle for Spoons, Forks, or Similar Articles; and I do hereby declare the following, when taken in connection with the accompanying drawing and the letters of reference marked thereon, to be a full, clear, and exact description of the same, and which said drawing constitutes part of this specification and represents a face view of a handle for a spoon embodying my design.

This invention relates to a design for a handle for spoons, forks, and similar articles.

As herein shown, the design consists of a handle expanding from its inner to its outer end, but with irregular edges, and the face is ornamented by narrow beads A on opposite sides near the inner end, between which is a row of floriated scrolls B. These scrolls form

a continuation of a series of scrolls C on opposite sides of the handle, near the central portion thereof, and these in turn are followed by floriated scrolls D, which merge into an elaborate scroll-tip E, the scrolls around the edge of the spoon forming an irregular edge. At the outer end a panel F is inclosed by two narrow bead-like scrolls G, all as shown in the accompanying illustration. 30

I claim—

The design for a handle for spoons, forks and similar articles as herein shown and described.

In testimony whereof I have signed this 35 specification in the presence of two subscribing witnesses.

WALTER L. WILKS.
